Des. 203,849
Patented Feb. 22, 1966

203,849

CARVING BOARD

Bela B. Neval, 92 Judson Ave., Dobbs Ferry, N.Y.

Filed June 17, 1965, Ser. No. 85,778

Term of patent 14 years

(Cl. D44—1)

FIG. 3.

FIG. 4.

FIG. 1 is a front perspective view of a carving board embodying my new design;

FIG. 2 is a top view of the carving board;

FIG. 3 is a front view of the carving board; and

FIG. 4 is a sectional view of the carving board on line 4-4 of FIG. 2.

I claim:

The ornamental design for a carving board, as shown.
